TOY

Ben Richter, Flushing, N. Y.

Application March 4, 1938, Serial No. 193,869

1 Claim. (Cl. 46—183)

This invention relates to hollow rubber toys for children or household animal pets, and particularly to hollow rubber toys provided with sound devices or voices.

5 An important object of this invention is the provision of a hollow rubber toy of improved construction which is durable in use and inexpensive to manufacture.

10 Another object of this invention is to provide a hollow rubber toy having improved means for retaining a sound device or voice in the inside thereof.

15 Other objects of this invention, together with certain details of construction and combinations of parts, will appear from the following detailed description and the appended claims.

20 Hollow rubber toys of the type contemplated by the instant invention, as heretofore commonly constructed, had substantially thin walls and therefore had a relatively short life particularly when given to a pet dog or cat as a plaything. Such hollow rubber toys necessarily had to have thin walls when they were provided with a sound device or voice which was adapted to emit a 25 sound when air is forced in or out of the rubber toy by manipulation of the wall thereof, as by pressing the wall and releasing the pressure. The hollow rubber toy of the instant invention is provided with a heavy wall for substantially its 30 whole surface which construction makes for a strong toy capable of surviving rough usage as from the teeth of a household pet animal.

35 The hollow rubber toy of the present invention is adapted to receive a sound device or voice which emits a sound when the toy is tipped in any direction. To this end the rubber toy is provided with an opening having thin elastic lips through which the sound device is inserted. The sound device is preferably of larger size than the 40 normal opening of the rubber toy, the construction and arrangement being such that the lips retain the sound device or voice within the rubber toy after its insertion therein.

45 The invention will now be described in greater detail, particularly with reference to the drawing wherein the preferred embodiments of my invention are shown. It is to be understood, however, that this description is given by way of example only and is in no way limitative.

50 In the drawing:

Figure 1 is a cross-sectional view of my improved hollow rubber toy showing the substantially heavy wall and the sound device or voice on the inside of the rubber toy;

55 Figure 2 is a view, partly in section, of the hol-

low rubber toy made in the form of the head of an animal;

Figure 3 is a cross-sectional view taken on line 3—3 in Figure 2, showing a number of ribs formed on the inside of the hollow rubber toy 5 for the purpose of retaining the sound device or voice in position therein;

Figure 4 is a view, partly in section, showing a modified form of my invention wherein a plate is inserted over the opening in the rubber toy for 10 the purpose of affording protection to the sound device or voice, and

Figure 5 is a bottom plan view of the rubber toy shown in Figure 4.

Like reference numerals indicate like parts 15 throughout the several views of the drawing.

Reference numeral 6 indicates a hollow substantially spherical body preferably made of rubber, although any other suitable material may be employed. The wall of the hollow body is of a 20 varying thickness, being thicker at its upper portion as shown at 7, and tapers gradually as it approaches an opening 8 at the bottom of the body. The opening 8 is surrounded with a flat annular ring 9 which is integral with the wall of 25 the hollow body. As is shown in Figure 2, the outer surface of the hollow body 6 may be molded in the form to simulate an animal's face.

The thickness of lip 9 is preferably such that the lip is quite elastic so that a sound device or 30 voice 11, which has a housing or casing 12 of larger diameter than the normal opening of lip 9, may be passed through the opening 8. The lip 9 serves to retain the sound device or voice 11 within the hollow body, i. e. it prevents the 35 voice from falling out once it has been inserted within the hollow body.

The sound device or voice 11 is of a type which 40 comprises a casing on the inside of which is attached a weighted cloth bellows. When the housing is tipped or inverted, the weight causes the bellows to contract and expand thereby causing a sounding element carried by the bellows to emit a sound or noise. One of the end closure members, such as is shown at 13 in Figure 1, is 45 perforated to permit the sound or noise to leave the housing 12.

The housing is preferably of such size as to contact the upper inside wall of the hollow body to prevent the sound device or voice from bouncing around on the inside of the body. To this end, the inside of the hollow body is provided with ribs 14, which may be molded integral with the hollow body, adapted to hold the sound device or voice firmly in position within the body. 50 55

In the modification shown in Figures 4 and 5, the lip 9 is provided with an annular groove 15, which groove is adapted to receive a perforate metal plate 16. This metal plate is adapted to protect the closure member 13 which is usually of paper from the teeth of the household pet animal, or the exploring fingers of a child.

The toy of my invention is particularly attractive to children and pet animals since the slightest movement of the toy causes a sound or noise to be emitted therefrom; there is no need to compress the wall of the toy. Accordingly, I may form the wall of the toy of hard rubber or sponge rubber of such thickness which makes it difficult to compress the same. The thick wall may be bitten into by the sharp teeth of the pet animal without destroying the toy or in any way impairing its usefulness.

While the invention has been described as being preferably made of rubber, it will readily be appreciated that, since it is not necessary for the operation of the sound device that the wall of the toy be compressed, the wall of the toy may be

made of substantially rigid construction as, for example, from pyroxylin, artificial resins, organic derivatives of cellulose such as cellulose acetate, cellulose ethers such as benzyl cellulose or any other synthetic materials.

It is to be understood that the foregoing detailed description and drawing are given merely by way of illustration and that many variations may be made therein without departing from the spirit of my invention.

Having described my invention, what I desire to secure by Letters Patent is:

A toy having a substantially spherical hollow rubber body having an opening therein, the wall of said body varying in thickness tapering toward said opening and being bent at said opening to form a flat, elastic lip, a sound device within said hollow body, ribs on the inside of said body for preventing movement of said sound device relative to said body, and a perforate metal plate 15 mounted in said lip for covering said opening.

BEN RICHTER.
